CARRIER-CURRENT TELEGRAPH SYSTEM

Montford Morrison, Upper Montclair, N. J.

Application August 13, 1943, Serial No. 498,496

2 Claims. (Cl. 178—53)

This invention relates to carrier telegraph systems, in which the separation of the transmitted signals, at the receiving terminals, is accomplished by electrical filter circuits.

Among the objects of this invention is to provide a selection of carrier-current frequencies which are conducive to a reduction in channel interference in the receiving circuit filters; to provide a selection of carrier-current frequencies which allows the operatively successful use of smaller and simpler separation filters in the receiving circuit; and to provide a better overall quality of signal reception in carrier-current telegraph systems.

These and other objects will be obvious upon reading the specification in connection with the accompanying drawing, in which Fig. 1 shows a conventional diagram of one class of electrical filter circuit in which my invention may be embodied; Figs. 2 and 3 are curves illustrating some of the theory of the invention; and Fig. 4 is a listing of odd harmonic components, set up for easy reference.

In the prior art, difficulty arises in the receiving circuit channels of carrier telegraph systems from two sources of interference between the separate channel filters.

One source of interference between separation channel filter circuits is due to the transit currents in the adjacent filters. Another source of interchannel interference is found where one channel is operating on an harmonic of another channel, and this may be either a higher harmonic or a sub-harmonic of the channel causing the interference, and it is this second-mentioned class of interference that the present invention eliminates.

Referring to Fig. 1, this shows a conventional telegraph carrier circuit in the most generalized form in which 1, 2 and 3 are alternating current generators; A, B and C comprise the corresponding station terminal apparatus on the transmission end; 4 is the transmission circuit; D, E and F are the separation filters at the receiving station terminal; and resistors 5, 6 and 7 are used to illustrate loads in the circuits.

If the filters D, E and F comprised perfectly-matched filter elements and had only one frequency impressed upon each, no reflections would be caused by the loads 5, 6 and 7. However, as it is not possible to prevent some reflections from the load circuits, and because the receiving filter elements are not perfectly matched, some reflections occur and some oscillations may exist within the filters themselves.

I have discovered that interferences between channels from the above causes lie mainly between channels which employ harmonics, one of the other, either a higher or a sub-harmonic.

5 Referring to Fig. 4, the numerals listed from 5 to 33 represent the harmonic components of some fundamental, and I have discovered that the 5th harmonic tends to interfere with the 15th; the 7th tends to interfere with the 21st; the 9th tends to interfere with the 27th; and so on.

It is American practice to use only odd harmonic components of given fundamental, in carrier telegraph transmission systems because of 15 the sum-and-difference harmonics that are generated in the amplifier tubes; and therefore, I am giving in the present embodiment, those harmonics which are commonly used in this country, although my invention is not limited to any 20 particular series of harmonics.

In any tuned circuit, such as a receiving circuit filter, where there is an accumulation of energy by reflection or by resonance itself, this accumulation is magnified between the fundamental and an odd harmonic due to the availability of energy in one harmonic, in such a phase relation, as tends to transfer it to a circuit of another odd harmonic frequency.

25 Referring to Fig. 2, where 8 represents the sine curve of energy, say, in filter D and 9 represents the current in filter F, it will be observed that the average current of the 3rd harmonic is shown as a positive value, during the same half-period as the fundamental 8 has a positive value, and likewise, the average value of the 3rd harmonic for the second half-period of the fundamental is negative when the fundamental has a negative value; therefore, these two circuits would, under favorable conditions, tend to exchange energy between 30 them. Referring to Fig. 3, where a second harmonic is illustrated, the case at point is not true.

I therefore find that if I use such a series of harmonics that one is not evenly divisible into another, inter-channel interference from these 45 causes is eliminated.

Referring to Fig. 4, for instance, if I desire 5 channels, I may use any 5 harmonics that are not evenly divisible one into the other, and if I desire 50 7 channels, I may use any 7 harmonics that are not evenly divisible one into the other. As a matter of illustration, I show that for 5 harmonics, I prefer to use the 5th to the 13th, inclusive; for 7 harmonics, I prefer to use the 7th to the 19th, inclusive; for 9 harmonics, I prefer to use the 9th

to the 25th, inclusive; and for 11 harmonics, I prefer to use the 11th to the 31st, inclusive.

By the elimination of inter-channel interference, due to oscillations and/or reflections occurring in the filters themselves, the filters embodied in my invention may be built which do, in fact, have reflections in them and/or may be oscillatory in design themselves. This means that a load resistor, if and when used, may have a lower resistance than called for by the filter design to eliminate reflections and/or oscillations. This means that the filter may be made smaller and less expensive than in the case of having to provide a design employing critical damped characteristics.

My invention is particularly adapted to carrier telegraph channels where terminal load resistors are not used, such as employed in super-audio carrier telegraphy which commonly employs frequencies between 3,000 and 10,000 cycles.

Commensurable, as used herein, is defined as "having a common measure; capable of being exactly measured by the same number, quantity, or measure; or expressible as integral multiples of some common unit." Incommensurable, as used herein, is defined "not commensurable."

While I have given in only one embodiment an adequate amount of direction to those skilled in the art to which my invention appertains, to make and use same, I do not limit myself to the embodiment shown, and give the scope of my invention in the claims hereunder.

What I claim is:

1. The method of carrier-current telegraph transmission, which comprises transmitting carrier frequencies of a continuous sequence of a mathematical series, said frequencies transmitted being only consecutive odd multiples of a single fundamental frequency, and each of the frequencies transmitted being indivisible evenly by any other of said frequencies transmitted.
- 10 2. In a multi-channel telegraph system, a single transmission circuit, a combination of carrier frequencies in said circuit, said frequencies being represented by a finite sequence of a Fourier series having consecutive odd terms only, and each frequency in said finite sequence being indivisible evenly with any other frequency in said finite sequence.
